UNITED STATES PATENT OFFICE.

HENRY C. BARNES, OF KALAMAZOO, MICHIGAN.

REINFORCING IN CONCRETE.

1,167,615.

Specification of Letters Patent. Patented Jan. 11, 1916.

Application filed November 30, 1914. Serial No. 274,839.

To all whom it may concern:

Be it known that I, HENRY C. BARNES, a citizen of the United States, residing at Kalamazoo, in the county of Kalamazoo, and State of Michigan, have invented certain new and useful Improvements in Reinforcing in Concrete; and I do declare the following to be a full, clear, and exact description of the invention, such as will enable others skilled in the art to which it appertains to make and use the same.

This invention relates to reinforced concrete construction, but more particularly to devices used to maintain the reinforcing material or elements in adjusted position.

One object of this invention resides in providing a means to facilitate the use of wire mesh as reinforcing material.

A further object of the invention is to provide a simple means for reducing the amount of time and labor required in constructing reinforced pavements and the like.

A still further object of my invention resides in designing a novel member having means to retain the same in a fixed position, and other means to coöperate with the rods or wires composing the reinforcement to retain the latter in proper position.

Another object is to provide an anchoring member having means to prevent its disengagement after being seated.

With these and other objects in view, my invention consists of certain novel details of construction, combination and arrangement of parts to be more particularly hereinafter set forth in the claim.

In the accompanying drawings in which corresponding parts are indicated by similar reference characters throughout the several views, Figure 1 is a top plan view illustrating the manner of disposing my improved anchoring irons; Fig. 2 is an enlarged side elevation of one of the anchoring irons; Fig. 3 is a transverse vertical section taken on the line 3—3 of Fig. 1; Fig. 4 is a horizontal section taken on the line 4—4 of Fig. 2, and Fig. 5 is a horizontal section taken on the line 5—5 of Fig. 2.

In constructing pavements and the like, it is frequently required that they be provided with reinforcing material interposed between the base and wearing course of the pavement. As the reinforcing material employed is usually in the form of a wire mesh which latter is shipped in rolls, it can be readily perceived what a difficult mat-

ter it is to properly lay the same, inasmuch as owing to its previously rolled condition, it naturally tends to resume the rolled state, and consequently much time and labor is required in laying the wire mesh so that it will lie perfectly flat. However, actual practice has demonstrated that no matter how carefully this wire mesh or screening may be laid, nevertheless, it will bulge at various points, the result of which is the formation of cavities in the pavement structure, with the result that the life of the latter is materially shortened.

To overcome the foregoing disadvantage and difficulty it is the purpose of this invention to provide a member which may be driven into the partially completed pavement, and having means at one extremity to engage the wires composing the reinforcing screen, whereby it will, after laying, be securely maintained in an even position, all of which will be more definitely pointed out in the detailed description hereinafter to follow.

Referring more particularly to the drawings, A indicates a partially completed concrete pavement. 1, a wire screening laid thereon which when the pavement is completed will be disposed between the base and wearing surface thereof. A plurality of anchoring irons 2, the latter consisting of an annular body section 3 having struck therefrom in staggered relation, the tongues 4, said tongues being laterally projected from the body 3 to form spurs, so that when said body is forced into the concrete mixture, owing to the particular disposition of the tongues 4, it will be prevented from subsequently working its way upwardly through the concrete, as will be readily understood without further description. The upper end of the body 3 is bifurcated longitudinally as at 5 and the bifurcations are curved outwardly and downwardly to produce the arcuate shaped fingers 6, said fingers being adapted when the anchoring irons are disposed in a mesh of the wire screen, to engage and overlie the wires composing the latter, as clearly shown in Fig. 3.

As it frequently transpires, the concrete has partially hardened before the screening is disposed thereon, therefore to enable the body 3 to be readily forced downward through the concrete mixture, said body 3 has its lower end flattened as at 3' and the

longitudinal edges of the flattened portion are curved outwardly in opposite directions to form wings 7, which produce a spiral at this end of the body, and consequently enable the latter to be readily inserted into the concrete, as will be readily understood without further description.

From the foregoing, it will be obvious that to permanently secure a given length of wire screen in a fixed position, the anchoring irons 2 are passed through the screen at predetermined points thereon, and are then forced into the concrete so as to bring the fingers 6 into engagement with the wires composing the screen, which will then permanently and securely maintain the screen in a proper position. In this connection it is also to be noted that these anchoring irons may also be employed for interlocking the various stretches of wire screening composing the reinforcement. In other words, where one screen overlaps the other, one of the anchoring irons may be driven into the concrete so as to have one of its fingers engage one of the wires of the underlying screening, and the other finger engaging one of the wires of the overlying screen.

Although in the foregoing description I have specifically referred to the utilization of my improved anchoring iron in connection with reinforcing material in the form

of a screening, but I do not however desire to limit myself to this particular form of reinforcement, inasmuch as the fingers 6 on body 3 could just as conveniently engage two ordinary reinforcing rods if the latter were arranged in parallel relationship, in a concrete mixture as the body 3 forced through the latter and between said rods would engage the same as will be readily understood without further description.

Thus it will be seen that I have provided an extremely simple article which will enable a concrete pavement using wire mesh as a reinforcing material to be constructed with less difficulty and more efficiency.

I claim:

An anchoring iron of the character set forth comprising a body, a plurality of spurs arranged thereon, said body having one end bifurcated, said furcations being arcuately extended in opposite directions to form fingers, and boring means formed at the other extremity of said body substantially as and for the purpose set forth.

In testimony whereof I have hereunto set my hand in presence of two subscribing witnesses.

HENRY C. BARNES.
